United States Patent Office.

WILLIAM T. KENNEDY, OF NEW YORK, N. Y.

Design No. 4,992, dated June 13, 1871.

DESIGN FOR A FORK OR SPOON-HANDLE.

The Schedule referred to in these Letters Patent and making part of the same.

To all whom it may concern:

Be it known that I, WILLIAM T. KENNEDY, of the city, county, and State of New York, have originated and produced a new and original Design for the Handles of Spoons and Forks, of which the following is a specification.

The nature of my design is fully represented in the accompanying photographic illustrations, to which reference is made, in which my design for the front and

back portions of the handle of a spoon or fork is shown.

I claim as my invention—

1. The design for the front of the handle, as shown.
2. The design for the back of the handle, as shown.

WILLIAM T. KENNEDY.
